ELECTRIC APPARATUS

Application filed January 24, 1927. Serial No. 163,227.

Our invention relates to electric apparatus generally and to the relations and the mounting of spark producing and associated elements particularly.

- 5 One of the objects of our invention is to prevent the exposure of sparks created between contact make and break members of an electric apparatus while the contact members are in normal use.
- 10 Another object of our invention is to provide a means which necessitates the locking of one or more contact make and break members into inoperative position before another contact make and break member can be operated.

Another object of our invention is to prevent the operation of one or more contact make and break devices while one or more contact make and break devices are exposed.

- 15 Another object of our invention is to provide an electric circuit between a storage battery and a motor with means for preventing a charging plug to be inserted in the circuit while the motor is inserted in the circuit and with means which necessitates the opening of the motor circuit in an enclosed chamber before the charging plug can be inserted.

Another object of our invention is to provide an electric storage battery locomotive, or other similar device, with means for preventing the sparking of the electrical make and break devices thereof from setting fire to gases or other objects surrounding the device.

In many instances, as in mines for instance where gas exists in the air, it is quite well known that open sparks or open fires cause explosions or fires. Electrical apparatus is a necessity in the mines mentioned as well as in various other places. An electric apparatus necessarily has contact make and break devices which do spark.

The present invention aims to prevent electric sparks from causing the explosions or fires mentioned.

In many instances, as in storage battery locomotives for instance, the battery requires re-charging; when an attempt is made to insert the charging plug while the motor

is in circuit or when the circuit is otherwise closed, there will be trouble if not disaster. The present invention aims to prevent the trouble or disaster arising from such causes.

Many electrical apparatuses are operated by unskilled labor who will push or pull on anything which moves to see what happens and thereby cause considerable trouble. The present invention aims to eliminate movable parts on the outside as far as possible and to so arrange the necessarily movable parts that no damage can result from the moving thereof.

Our invention is illustrated in the accompanying drawings which show one embodiment of our invention, as applied to a storage battery locomotive.

We are aware, however, that our invention is applicable to other devices also.

In the accompanying drawings:—

70 Fig. 1 is a side view of a device having a number of contact make and break devices inclosed therein, which embodies the features of our invention, and showing the cover in closing position and the operating handle for the switch in the position it is in when the switch is open, and the dog in a position to lock the operating handle in that position and to permit the charging plug, or other connector, to be either removed from or inserted into the device.

75 Fig. 2 is a side view similar to Fig. 1 and shows the operating handle for the switch in the position it is in when the switch is closed, and the dog in a position to permit the handle to be operated to open and to close the switch and to prevent the charging plug, or other connector, from being either removed from or inserted into the device.

80 Fig. 3 is a front view of Fig. 1 showing the cover in sealing or closing position and the operating handle for the switch in operable condition.

85 Fig. 4 is a front view of Fig. 1 showing the cover in unsealing or uncovering position to expose the fuses and the operating handle for the switch in locked position.

90 Fig. 5 is a section, taken in a horizontal plane indicated by the line 5—5 in Fig. 1,

and shows more clearly the relations between the cover and the switch mechanism and the fuses and the contact mechanism.

Fig. 6 is a section, taken in a horizontal plane indicated by the line 6--6 in Fig. 4, and shows more clearly the relations between the cover in open or unsealing position and the lock and arm and step mechanism when the cover is in that open position.

Fig. 7 is a general perspective view of a storage battery locomotive with the device shown in Figs. 1 to 6 attached thereto.

Similar reference characters refer to similar parts throughout the views.

The device illustrated in detail in the accompanying drawings is shown as applied to a storage battery locomotive which has the battery A, the motor B, the controller C, the circuit D; and switch and contact make and break elements inclosed in the device which is designated as E.

The device E, in the present instance made as one unit attachable to the locomotive or other apparatus, has a housing with one side open to permit the machining of the interior thereof and to permit the installation of elements therein; the removable wall 10 is secured to the housing over the open side to completely close the housing.

The wall 10 has the internally threaded opening 11 through it and the cover 12 is threaded into the opening 11 and has the flange 13 to limit the inward movement of the cover and also has the lugs 14 to facilitate the screwing or the unscrewing of the cover into or out of the wall 10. The cover 12 has the journal stud 15 projecting outwardly therefrom for the purpose appearing presently.

The switch F and the fuses G and the contact elements H are mounted within the housing. The fuses G being disposed directly opposite the opening 11 so that the same can readily be re-newed through this opening when the cover 12 is removed from this opening.

The switch F, in the present instance a knife switch, is mounted on the rotatable shaft 16 which is journaled in the walls 17 and 18 of the housing and the end 19 thereof projects some distance beyond the outside of the wall 17. The boss 20 of the operating lever I is secured to the end 19 in such a manner that the handle portion 21 of the lever I extends horizontally as seen in Fig. 1 when the switch is open and extends vertically as seen in Fig. 2 when the switch is closed.

The dog J is journaled on the stud 22 on the outside of the housing and has the ears 23 to facilitate the rotation thereof on the stud 22.

The dog J has the flange 24 the outer edge of which has the outwardly arcuate surface 25 concentric with the longitudinal axis of the stud 22 and the inwardly arcuate surface 26 adjacent to the surface 25. The flange 24 also has the toes 27 and 28 for purposes appearing presently.

The dog J also has the hollow housing 29 having the arcuate wall 30 with the arcuate notch 31 therein.

The lever I has the flange 33 the outer edge of which has the outwardly arcuate surface 34 concentric with the longitudinal axis of the shaft 16 and of substantially the same contour as, and complementary to, the inwardly arcuate surface 26 of the dog J and also has the toes 35 and the inwardly arcuate surface 36 adjacent to the surface 34 and of the same contour as, and complementary to, the outwardly arcuate surface 25 of the dog J. The flanges 24 and 33 and the distance between the longitudinal axis of the shaft 16 and the stud 22 are arranged so that the component surfaces 25 and 36 contact each other when the dog J and the lever I are in the positions shown in Fig. 1 and so that the component surfaces 26 and 34 clear each other when the dog J and the lever I are in the positions shown in Fig. 2.

The boss 37 is provided on the wall 10 and the stem 38 is journaled therein and is longitudinally movable therein. The lock head 39 is provided on the inner end of the stem 38 and extends into the hollow of the housing 29 and is clear of the walls thereof when the cover 12 is in the position of closing the housing E as shown in Fig. 5. The head 39 can move longitudinally outward from this position with the stem 38 so that the head 39 engages the arcuate notch 31 when the cover 12 is in the position of opening the housing E as shown in Fig. 6.

The arm K has the journal boss 40 with the stud 41 rotatable therein and the boss 41 which is pinned to the stem 38 so that the arm K can rotate on the stem 38 and so that the stem 38 with the head 39 thereon is moved longitudinally when the arm K is moved longitudinally.

The contact element 42 is mounted in the housing E and has the contact make and break sockets 43 and 44 mounted therein and inserted in the circuit D.

The plug L, either a battery charging plug or a motor connector plug, or other connector plug, has the end 45 fitting slidably but closely into a bore in the housing to seal or close the housing as far as possible and also has the contact make and break plugs 46 and 47 adapted to the sockets 43 and 44 respectively and inserted in the circuit D.

The plug L has the flange 48 and the diametrically reduced portion 49 adjacent to the flange for engaging or disengaging the toe 28 of the dog J as will appear presently.

The arm K has the lug 50 and the boss 37 has the step comprising the surfaces 51, 52, 53 and 54 for purposes appearing presently.

Normally, the cover 12 and the plug L seal the housing of the device E completely so that the contact make and break elements, as the switch F or the fuses G or the element H, are completely inclosed in the housing to prevent any sparking thereof from being conveyed to or in any manner reaching the outside of the element E.

Since the end 45 of the plug L fits into and extends some distance into the housing, contact between the plugs 46 and 47 and the sockets 43 and 44 can only be made or broken while the end 45 is still in the housing; therefore, any sparking which does take place between the contact plugs and the sockets is confined within the housing and can not be communicated to the outside of the housing.

When the switch F sparks during the operation thereof, or at other times, the sparks are confined to within the housing as long as the cover 12 is in closing position.

When one or both of the fuses G blows during the normal operation of the device, the sparks created by such blowing are confined to within the housing as long as the cover 12 is in closing position and can not be communicated to the outside of the housing.

The blowing of fuses is of quite frequent occurrence in an electrical apparatus and requires the re-newal of the fuses and such re-newal will cause sparking if it is attempted while the circuit D is otherwise closed.

In order to prevent the re-newal of the fuses while the circuit D is otherwise closed, we provide the lock mechanism for the switch as described which operates as follows:

When the cover 12 (journaled on the stud 15) is unscrewed (out of the wall 10) it moves longitudinally outward and moves the arm K with it in the same direction through the boss 40.

This outward movement of the arm K moves the stem 38 longitudinally in the same direction (boss 41 of the arm pinned to the stem) and thereby moves the head 39 into the arcuate notch 31 and thereby prevents the dog J from being rotated. The notch 31 is so located that the head 39 can enter the notch 31 only when the dog J is rotated into the position shown in Fig. 1 where the switch is open and the lever I is in such a position that the surfaces 25 and 36 are in contact. This contact of the surfaces 25 and 36 prevents the operation of the lever I and consequently prevents the closing of the switch.

When the cover 12 is in closing position (screwed into the wall 10) the head 39 clears the inside of the walls of the housing 29 and thereby permits the rotation of the dog.

When the dog J is rotated into the position shown in Fig. 2, the surface 34 of the lever I clears the surface 26 of the dog and thereby permits the operation or rotation of the lever and, consequently, permits the opening as well as the closing of the switch while the dog is in this rotated position. Therefore, the dog can be rotated only while the cover 12 is in closing position to permit the operation of the lever I and the opening and the closing of the switch F and the dog J can not be rotated out of the position of locking the switch in open position while the cover 12 is uncovering the opening in the wall 10.

Since the arm K is secured to the rotatable stem 38, the boss 40 thereof can move in an arc with the longitudinal axis of the stem as a center. Since the cover is journaled in the boss 40, it moves therewith in the same arc when the cover is unscrewed from the wall 10.

When the cover 12 is in closing position, the outer end of the lug 50 is disposed freely between the surfaces 53 and 54; the contact between the inner end of the lug 50 and the surface 53 aiding to retain the longitudinal axis of the cover 12 substantially in alignment with the longitudinal axis of the opening in the wall 10 and thereby eliminates the necessity of holding up the weight of the cover while the same is being unscrewed from or screwed into the wall 10.

After the cover 12 is screwed out of the wall 10, the inner end of the lug 50 clears the surface 52 and permits the same to travel downwardly in an arcuate path until it abuts the surface 51 whereupon further movement of the cover in that direction is arrested and the same is automatically held in the position shown in Fig. 4 where it is seen that the fuses G are exposed through the opening in the wall 10 so that they can be renewed or manipulated in any manner.

When the cover 12 is in the position shown in Figs. 4 and 6, the inner end of the lug 50 abuts the surface 54 and thereby prevents the lock stem 38 from moving inward while the cover is in this position and thereby retains the head 39 in locking engagement with the notch 31 so that it is impossible to close the switch while the cover is in this position.

Since the cover can be removed only by locking the switch in open position and since the locking can be effected only by and during the removal of the cover, it is impossible to expose the fuses while the circuit D is otherwise closed.

When the plug L is inserted in the hous-

ing and the dog is rotated into the position shown in Fig. 2, the flange 48 is disposed between the toe 28 and the wall of the housing; therefore, the plug L can not be removed from the device E while the switch is capable of being operated.

When the dog is rotated into the position shown in Fig. 1, the switch is open and is locked against operation and the toe 28 10 clears the flange 48; therefore, the plug can be inserted or removed only when the switch is open.

The toes 27 and 35 act as abutments to limit the travel of the dog and of the 15 lever.

We are aware that our invention is applicable to devices other than that shown and described and that changes may be made in the structure and in the arrangement of elements shown and described within the scope of the appended claims; therefore, without limiting ourselves to the precise application of our invention as shown and described nor to the precise structure 20 and arrangement of elements as shown and described,

We claim:—

1. An electric apparatus having a housing having an entrance opening and a removable cover for said opening, electric contact make and break devices and a fuse device confined in said housing, means on said housing for operating one of said make and break devices, and a movable member between said cover and said operating means and moved by a removal movement of said cover before the same uncovers any part of said opening to lock said operating means against operation thereof.

40 2. An electric apparatus having an electric circuit having a switch and a concealed fuse inserted therein, movable means adapted to expose said fuse, and means operated by said exposing means during the initial 45 movement thereof and before said fuse is exposed to lock said switch against the closing thereof.

3. An electric apparatus having an electric circuit having a switch and a concealed 50 fuse inserted therein, movable means for exposing said fuse, and a movable member normally permitting the operation of said switch and movable into a position to lock said switch against operation thereof before 55 said fuse is exposed and moved into said position by the operation of said movable means and retained in said position by said movable means while the same is in position of exposing said fuse.

60 4. An electric apparatus having an electric circuit having a switch and a concealed fuse inserted therein, means for operating said switch, a removable cover for exposing said fuse, a dog manually movable into two 65 positions and having means for permitting

the operation of said operating means when said dog is in one of said positions and means for locking said operating means against the closing of said switch when said dog is in the other one of said positions, and 70 movable means operated by and during the removal of said cover and locking said dog in said other position before said fuse is exposed.

5. An electric apparatus having an electric 75 circuit having spaced contacts and a switch and a concealed fuse inserted therein, a contact plug to contact said contacts, a dog movable into two positions, means between said dog and said switch to retain 80 said switch in open position while said dog is in one of said positions, means between said dog and said plug to prevent said plug from contacting or from separating from said contacts while said dog is in the other 85 one of said positions, a cover movable to expose said fuse, and lock means between said cover and said dog to lock said dog in said one position and operated by the movement of said cover and retained in 90 locking position by said cover while the same is moved to expose said fuse.

6. An electric apparatus having an electric 95 circuit having spaced contacts and a switch and a concealed fuse inserted therein, a contact plug to connect said contacts, a cover movable to expose said fuse, and means operated by the initial opening movement of said cover and before said cover starts to expose said fuse to prevent the 100 closing of said switch while said fuse is exposed.

7. An electric apparatus having a closed 105 housing having an entrance opening and a cover removable from said opening, an electric circuit having spaced contacts and a switch and a fuse inserted therein and enclosed in said housing, a contact plug to connect said contacts, a dog journaled on said housing and having means to lock said 110 switch in the open position thereof, and means to prevent the making and the breaking of contact between said plug and said contacts while said switch is closed and while said switch is free to be closed, a lock 115 to retain said dog in position to lock said switch in said open position, an arm between said cover and said lock and moved by the uncovering movement of said cover to effect said locking of said dog and having means to retain said locking while said fuse is exposed.

8. A casing having an opening in a wall 120 thereof, mechanism carried by said casing and having a movable member, and a removable cover for said opening having a portion telescopic into said opening to prevent uncovering of said opening during a portion of the movement of the cover and being operatively connected with said mov- 125

able member so that said movable member is moved into one relation to said mechanism while said portion is telescoping out of said opening and into another relation to said mechanism while said portion is telescoping into said opening.

9. A casing having a threaded opening in a wall thereof, mechanism carried by said casing and including a movable member, and 10 a removable cover for said casing having a threaded portion screwable into said opening and being operatively connected with said movable member so that said movable member is moved into one relation to said 15 mechanism while said portion is being screwed out of said opening and into another relation to said mechanism while said portion is being screwed into said opening.

10. A casing, an operable mechanism in 20 said casing, operating means for said operable mechanism, a removable cover for said casing, and a lock mechanism operatively connected with said operating mechanism and with said cover so that the removal of 25 said cover from said casing locks said operating means against operation before said cover uncovers said casing and the attachment of said cover to said casing releases said operating means for operation thereof.

30 11. A casing having an opening in a wall thereof, a movable mechanism in said casing, a lock mechanism for said movable mechanism, and a movable cover for said opening supported on said lock mechanism 35 and adapted to move a member of said lock mechanism into locking position while said cover is being removed from said opening and out of locking position while said cover is being placed over said opening.

40 12. A casing, a movable mechanism in said casing, a lock mechanism for said movable mechanism, a removable wall for said casing to facilitate installation of and access to said movable mechanism in said casing and having an opening therein, and a movable cover for said opening supported on a member of said lock mechanism and having a portion telescopic into said opening and adapted to move said member into and out of locking 50 position in said lock mechanism when said cover is moved from and onto said opening.

55 13. A casing, operable mechanism in said casing, a bar adjacent to said casing, a cover for opening and closing access to said operable mechanism in connection with said bar, and a step adjacent said casing to abut said cover mechanism and support said cover when the same is removed from said casing.

60 14. A casing, operable mechanism in said casing, a bar adjacent said casing, a cover mechanism for opening and closing access to said operable mechanism in connection with said bar, and a step adjacent said casing to abut said cover mechanism and support said cover while the same is being at-

tached to and removed from said casing.

70 15. A casing, operable mechanism in said casing, a bar adjacent said casing, a cover mechanism for opening and closing access to said operable mechanism in connection with said bar, and step means adjacent said casing to abut said cover mechanism and support said cover while the same is removed from said casing and while the same is being attached to and removed from said casing.

75 16. A casing, operable mechanism carried by said casing and including a pivoted flange member, a removable cover for said casing having a bar, and a pivoted member interlockable with said flange member and with said bar.

80 17. A casing, operable mechanism carried by said casing and including a pivoted flange member, a removable cover for said casing having a bar movable with the same, and a pivoted member interlockable with said flange member and with said bar; said members having component arcuate surfaces whereby pivotal movement of each of said members is prevented while pivotal movement of the other one of said members is permitted.

85 18. A casing, operable mechanism carried by said casing and including a pivoted flange member, a removable cover for said casing having a bar movable with the same, and a pivoted member interlockable with said flange member and with said bar; said members having component arcuate surfaces whereby pivotal movement of each of said members is prevented while pivotal movement of the other one of said members is permitted and movement of said bar is prevented while said pivotal movement of said interlockable member is prevented.

90 19. A casing, operable mechanism carried by said casing and including a pivoted flange member, a removable cover for said casing having a bar movable with the same, and a pivoted member interlockable with said flange member and with said bar; said members having component arcuate surfaces whereby pivotal movement of each of said members is prevented while pivotal movement of the other one of said members is permitted and movement of said bar is permitted while pivotal movement of said interlockable member is permitted.

95 20. A casing, operable mechanism carried by said casing and including a pivoted flange member, a removable cover for said casing having a bar movable with the same, and a pivoted member interlockable with said flange member and with said bar; said members having component arcuate surfaces whereby pivotal movement of each of said members is prevented while pivotal movement of the other one of said members is permitted and movement of said bar is prevented while said pivotal movement of said

interlockable member is prevented and movement of said bar is permitted while pivotal movement of said interlockable member is permitted.

- 5** 21. An electric apparatus including a casing, a removable cover for and in a sealing relation with said casing, said sealing relation continuing during the first part of the removal movement of said cover, an electric
- 10** device in said casing, operating means for said device, and lock and release means for said operating means operated by the first part of the removal movement to prevent operation of said operating means and by
- 15** attaching movement of said cover to permit operation of said operating means.
- 22. An electric apparatus including a casing, a removable cover for and in a sealing relation with said casing, said sealing relation continuing during the first part of the removal movement of said cover, an electric device in said casing, operating means for said device including manually operable interengageable means to permit and to prevent the operation of said operating means, and lock and release means for said manually operable means operated by the first part of the removal movement to prevent the operation of said operating means and of
- 25** said manually operable means and by attaching movement of said cover to permit the operation of said operating and manually operable means.

In testimony of the foregoing, we affix our
35 signatures.

EUGENE W. SCHELLENTRAGER.
WILLIAM E. BOYER.
